[57] CLAIM

The ornamental design for package for wrench sockets, as shown and described.

DESCRIPTION

FIG. 1 is a perspective view of package for wrench sockets showing my new design;
FIG. 2 is a front elevational view thereof;
FIG. 3 is a rear elevational view thereof;
FIG. 4 is a left side view thereof;
FIG. 5 is a right side view thereof;
FIG. 6 is a top plan view thereof;
FIG. 7 is a bottom plan view thereof; and,
FIG. 8 is a perspective view showing the article in use.
The broken line showing of the wrench and the sockets is for illustrative purposes only and forms no part of the claim.

FIG. 1

FIG. 2

FIG. 3
